UNITED STATES PATENT OFFICE.

WILLIAM HENRY WAKER, OF SOUTH NORWOOD, ENGLAND, ASSIGNOR OF ONE-HALF
TO SAMUEL PECK, OF WALLINGTON, ENGLAND.

PERCUSSIVE HAMMER, DRILL, AND THE LIKE.

1,114,075.

Specification of Letters Patent. Patented Oct. 20, 1914.

Original application filed June 16, 1913, Serial No. 773,993. Divided and this application filed February 14, 1914. Serial No. 818,692.

To all whom it may concern:

Be it known that I, WILLIAM HENRY WAKER, a subject of the King of Great Britain, and resident of South Norwood, in the county of Surrey, England, have invented new and useful Improvements in and Connected with Percussive Hammers, Drills, and the like, of which the following is a specification, being a division of my application Serial Number 773,993, filed June 16, 1913.

This invention relates to improvements in and connected with percussive hammer drills and like percussive tools.

15 The principal object of the present invention is to provide a simple and efficient combined valve and cylinder for such tools, the cylinder and valve, including the passages ports and working parts for giving admission exhaust and auxiliary exhaust, being so symmetrically designed and arranged that the cylinder and valve can be mounted in the tool with either end to the front, the main and auxiliary exhausts being led out 20 through the same exhaust connection under control of a throttle valve, the adjustment of which controls the working of the tool by varying the back pressure.

Other objects are to provide facilities for 30 valvular adjustments and for lubrication as will be hereinafter explained.

In order to enable the invention to be readily understood reference is made to the accompanying drawings in which:—

35 Figure 1 is a longitudinal section of a percussive hammer drill having the present improvements applied thereto; Fig. 2 is partly a plan and partly a section on the line II—II of Fig. 1; Fig. 3 is a vertical section 40 on the line III—III of Fig. 1; Fig. 4 is an elevation of the liner of the valve chest removed; Fig. 5 is an end view of a throttle valve adapted to be fitted to the exhaust of the tool and Fig. 6 is a plan of the valve 45 seen in Fig. 5.

In the drawings *a* indicates the cylinder in which the piston *b* reciprocates. The piston shown in Fig. 1 is formed or fitted with a rod *c* at each end the forward rod 50 being adapted to act as the hammer and to strike the reduced end *f* of the shank *g* of a

drill or the like at the end of the forward stroke. A piston formed or fitted at each end with a rod *c* is said to be double ended but the present invention is applicable not 55 only to such pistons but also to the usual type of single ended piston that is to say a piston having only a forwardly directed rod *c*. The latter is usually helically formed or threaded for working in a rotation nut *e* 60 which engages with a drill holding sleeve or chuck *x* for rotating the latter. In the example shown in the drawing the nut *e* is shown fitted with radially slideable pawls *z* which under the action of springs, 65 constantly engage internal ratchet teeth formed on the ring *s* which is rigidly held between the front head *p* and the front cover ring *q* of the cylinder *a*. The rear end of the cylinder *a* which is a counterpart of the front 70 end is closed by a cover ring *q* and the rear piston rod *c* works in a rear nut *e* the pawls of which engage a ratchet ring *s* rigidly held or clamped between the rear cover ring and a cover *j*. If a piston having only a 75 single rod *c* be used however, the rear nut *e* and ratchet and pawl mechanism are dispensed with and the rear end of the cylinder may be closed by an imperforate cover 80 which is substituted for the rear cover ring *q*. The present invention however concerns the symmetrical construction and arrangement of the cylinder *a* and its ports and passages and valve and before proceeding with a description of the latter it may be remarked that the cylinder is constructed 85 with two similar ends either of which may be arranged toward the front for engaging with the front cover ring *q*. In the event of an imperforate cover being substituted for the 90 rear cover ring as hereinbefore indicated such cover would be made similarly to the cover rings *q* so as to fit into either end of the cylinder.

The valve chest *24* which is advantageously made in one piece with the cylinder *a* is arranged centrally of the latter. The chest *24* comprises a central cylindrical space the axis of which is parallel with the axis of the cylinder and the ends of this space are 100 closed by plugs *25* formed with axial hollows or recesses *26* which communicate with cir-

cumferential grooves or passages 27 in the plugs through radial holes or ports 28. The grooves 27 are formed in such a position on their respective plugs that they come opposite respective ports 29 which communicate with passages leading to respective ends of the cylinder. Longitudinal passages 30 are formed in the wall of the cylinder by drilling holes from the ends to a point midway along the cylinder the outer ends of these holes being conveniently plugged by plugs 31. The ports 29 open into the passages 30 and ports 32 open from the passages 30 into the ends of the cylinder.

15 A tubular liner 33 is inserted into the central cylindrical space in the chest and is kept in the desired position by the plugs 25 which are screwed home against the liner 33. As will be apparent from Fig. 1, the plugs are 20 of such a length that either may be screwed in while the other is screwed out so that the liner may receive endwise adjustment which in some cases may be very advantageous as hereinafter explained.

25 The piston slide valve 34, is capable of free movement to and fro within the liner 33, its motion being arrested in either direction by the annular ends of the hollow plugs 25, which form seats for the respective end 30 faces of the piston valve 34. Each end of the piston valve 34 may be hollowed out centrally and for a distance axially as at 35, the hollow spaces in the valve and the plugs having the effect of cushioning the valve at the moment of seating. The external diameter of the end portions of the valve may be reduced as seen in Fig. 2 so that an annular and reduced area of the valve strikes and seats against a corresponding plug at each 40 end of the travel of the valve.

The admission 36 Fig. 3 for the pressure fluid or power medium is suitably at one side of the chest and the liner has preferably two sets of ports 37, 37 Figs. 3 and 4 on that side 45 adapted to be alternately covered and uncovered by the cylindrical body of the valve in its reciprocatory movements. The exhaust connection 38 is conveniently at the other side of the chest immediately opposite the 50 admission 36 and inclined ports or passages 39 are bored or formed from the main exhaust 38 to points situated near to the midway point in the length of the cylinder, as will be readily understood by reference to 55 Fig. 1 so that the piston b uncovers one or other of such exhaust ports 39 or sets thereof, as it nears the completion of each stroke. As seen in Fig. 3, the exhaust ports 39, 39 60 are in duplicate in order to provide adequate escape for the pressure fluid.

Referring to Fig. 1 and supposing the tool to be in operation, it will be seen that pressure fluid entering at the left hand end of the valve 34 and passing through the hollow

space 26, radial passages 28 and groove 27 in 65 the rear plug 25 and through the rear passages 29 and 30 and rear port 32 in the cylinder has driven the piston b forward. During the forward stroke of the piston b the valve 34 has been held against its seat on the 70 right hand plug 25 by the pressure fluid acting on the left hand or rear end of the valve but as the piston b reaches the end of its stroke it uncovers the rear exhaust port 39. In Fig. 1 the piston has fully uncovered this 75 port. The pressure behind the piston b and to the left hand of the piston valve 34 is suddenly lowered, as the piston b uncovers this port 39 and the back pressure or cushioning pressure in front of the piston b and to the 80 right hand of the valve 34 immediately acts upon the latter and quickly moves the valve 34 against the seat on the left hand plug 25 thereby admitting pressure fluid to the forward end of the cylinder and cutting it off 85 from the rear end. Thereupon the piston b is driven rearwardly and immediately covers the rear exhaust port 39 and upon the forward exhaust port 39 being uncovered near the end of the rearward stroke a reversal 90 will take place similar to that just described and the cycle of operations will be repeated so long as pressure fluid is admitted at 36, the working of the tool being controlled by checking or throttling the exhaust by a 95 throttle valve on the exhaust pipe.

It has been explained how the exhaust port or ports 39 on one side is or are covered by the piston soon after the latter has 100 reversed and commenced a stroke in the opposite direction. Now in order to prevent the pressure fluid which has not had time to escape to the exhaust from setting up a considerable back pressure, auxiliary exhaust ports 40 are formed say at the inner ends of 105 the longitudinal passages 30. These ports 40 may be comparatively small and are adapted to be alternately covered and uncovered by a groove or cavity 41 in the valve 34 which cavity 41 places the appropriate 110 one of these auxiliary ports in communication with an exhaust port or ports 420 formed in the liner 33 about midway between the ends of the latter as seen clearly in Fig. 2. The port 420 and the sets of admission ports 37 are so relatively disposed 115 that the valve 34 can never open a through-way from the admission 36 to the exhaust 38. As seen in Fig. 1 the outlet of the ports or passages 40 may be made of any desired 120 size by forming suitable holes 42 in the liner 33. In this figure, the valve 34 is shown in the position for relieving the back pressure in the forward end of the cylinder a It being assumed as stated that the piston it finishing 125 its forward stroke. By adjusting the liner 33 in one direction or the other by the aid of the screw plugs 25, as above described,

- the holes 42 may be moved wholly or partly out of register with the ports 40 thereby dispensing with or reducing the auxiliary exhaust as found desirable or convenient.
- 5 By attaching an exhaust pipe to the connection 38 and by having a throttle valve in said pipe the working of the tool may be effectually controlled by opening or closing the throttle on the exhaust and varying the 10 back pressure.

The check exhaust or throttle valve seen in Figs. 5 and 6 which is formed very advantageous, and may be fitted in the connection 38, comprises a hexagonal body 49 having screw threaded portions 50 at its two ends and a disk valve 51 pivotally mounted within its bore. The valve 51 is mounted upon the square portion of the spindle 52 which may slide in the diametrical sleeve portion or hole in the valve disk. The spindle 52 is normally depressed by say a spring 53 which keeps the lower pivotal portion 54 of the spindle 52 in its bearing and the handle 55 on the upper end of the spindle in engagement with serrations, notches, or projections 560 arranged on the body 49 in a part-circular series in known manner. The valve 51 may be opened or closed gradually after raising the handle 55 against the action of the spring 53 and the projections not only afford an indication of the degree of opening or closing of the valve but, when the handle 55 is released, interlock with the said handle 55 and maintain the valve in its 30 adjusted position. The spindle 52 may be suitably formed or packed to prevent escape of the fluid as will be readily understood.

It may be desirable to fit a lubricator to the valve chest 21 and this is conveniently accomplished by screwing an oil cap 43 to the chest on the top or outer side of the latter. The spigot portion 44 of the cup may be filled by a plug 45 having suitable perforations 46 adapted to come opposite perforations 47 in the liner 33, the last named perforations being in such a position that they can never be uncovered by the valve 34 at the same time as the valve uncovers the admission ports. A dowel or device 48 Fig. 3 50 may be formed on the plug 45 and may be adapted to reach and enter a longitudinal slot or groove formed in the liner 33. In this way the liner is prevented from turning or moving laterally while it is capable of endwise or longitudinal adjustment under the action of the screw plugs 25 in the manner hereinbefore described.

It will be noted that all the ports and passages are symmetrically constructed and arranged so that the apparatus works equally well and in an identical manner no matter which end is toward the front.

I claim:

1. A percussive tool, comprising a cylin-

der, a valve chest connected with the cylinder, a slide valve in the chest having cupped ends, a liner in which the valve slides, and hollow ported plugs screwed into the valve chest and forming seats for respective ends of the valve and adapted to axially adjust 70 the liner.

2. A percussive tool, comprising a cylinder, a piston hammer in said cylinder, a valve chest connected with the cylinder, a slide valve in the valve chest adapted to 75 control admission of pressure fluid to and exhaust from the two sides of said piston, a liner in the chest for said slide valve, and hollow ported plugs secured in the valve chest and forming seats for respective ends 80 of said valve and adapted to adjust said liner, the slide valve being formed with a cavity arranged to open one or the other of two auxiliary exhaust ports to the exhaust passage.

3. A percussive tool, comprising a cylinder reversible end for end, a piston hammer in said cylinder, a valve chest connected with the cylinder, a piston slide valve in the valve chest adapted to control admission of pressure fluid to and exhaust from the two sides of said piston, a liner in the valve chest for the slide valve, and hollow ported plugs in the valve chest forming seats for respective ends of said valve and adapted 95 to adjust said liner, the piston valve being formed between its ends with a cavity which is adapted to open one or the other of two auxiliary exhaust ports to the exhaust passage, said auxiliary exhaust ports being arranged near the middle of the cylinder at the inner ends of passages extending from ports at respective ends of the cylinder.

4. A percussive tool, comprising a cylinder reversible end for end, a piston hammer 105 in said cylinder, a valve chest connected with the cylinder, a piston slide valve in said chest adapted to control admission of pressure fluid to and exhaust from the two sides of said piston, hollow ported plugs secured 110 in the ends of the valve chest and adapted to act as seats for respective ends of said valve, each of said plugs being formed with ports communicating with the hollow space of the respective plug, said valve being formed 115 between its ends with a cavity adapted to uncover in alternation two auxiliary exhausts, the ports and passages of which are symmetrically formed in said cylinder, said auxiliary exhausts communicating with the 120 main exhaust when uncovered by said valve, and a throttle valve on the common exhaust connection.

5. A percussive tool, comprising a cylinder, a piston hammer in said cylinder, a 125 valve chest, a piston slide valve in the latter adapted to control admission of pressure fluid to and exhaust from the two sides of

said piston, a liner in the valve chest for said valve, hollow ported plugs secured in said valve chest and forming seats for respective ends of said valve and adapted to adjust said liner, and a lubricant receptacle comprising a spigot portion adapted to be secured in an aperture in said chest, said

spigot portion inclosing lubricant passages adapted to communicate with lubricant ports in said liner.

WILLIAM HENRY WAKER.
